3-INDOLEMETHANEPHOSPHONIC ACID AND ITS SALTS AND PREPARATION THEREOF

Noel F. Albertson, Castleton on Hudson, N.Y., assignor to Sterling Drug Inc., New York, N.Y., a corporation of Delaware

No Drawing. Filed July 28, 1958, Ser. No. 751,155

8 Claims. (Cl. 260—319)

This invention relates to 3-substituted indoles.

The present invention resides in the concept of a composition of matter having a molecular structure wherein a methanephosphonic acid radical, $-\text{CH}_2-\text{PO}_3\text{H}_2$, is attached to the 3-position of indole; the salts of such composition; a process for preparing the compositions; and intermediates in said process.

The physical embodiments of the inventive concept have plant growth regulant properties. In particular, they are inhibitors of heteroauxin (3-indoleacetic acid) and are thus useful as antagonists of plant growth.

The embodiment of the inventive concept can be accomplished by interacting a tri-lower alkyl phosphite and a 3-indole-methyl-quaternary ammonium salt having the structural formula

where B represents a member of the group consisting of dimethyl, diethyl, and 1,5-pentylene

($-\text{CH}_2\text{CH}_2\text{CH}_2\text{CH}_2\text{CH}_2-$)

radicals, and An represents a member of the group consisting of the iodide radical and the methosulfate radical, to produce a di-lower alkyl 3-indolemethanephosphonate, which ester is then hydrolyzed to produce 3-indolemethanephosphonic acid; and this dibasic acid can, if desired, be interacted with either one or two equivalents of an organic or inorganic base to form a corresponding organic or inorganic salt.

The term "lower alkyl" as used in the specification and claims represents in each instance branched and unbranched alkyl radicals having 1-4 carbon atoms and accordingly includes methyl, ethyl, isopropyl, n-butyl, and the like.

In the first step of the process of my invention, the tri-lower alkyl phosphites employed as a starting material are known and readily obtained compounds. The 3-indole-methyl-quaternary ammonium salt reactants are readily obtained by interacting an appropriate 3-(N,N-disubstituted aminomethyl)indole, that is 3-(N,N-dimethylaminomethyl)indole (gramine), 3-(N,N-diethylaminomethyl)indole, or 3-(piperidinomethyl)indole, with methyl iodide or dimethyl sulfate. It is not necessary to isolate the 3-indolemethyl-quaternary ammonium salt thus formed before interacting it with the tri-lower alkyl phosphite. In fact, it is ordinarily most convenient to interact a mixture of the 3-(N,N-disubstituted aminomethyl)indole, the tri-lower alkyl phosphite, and the methyl iodide or dimethyl sulfate, so that the quaternary ammonium salt is formed in situ and then reacts with the tri-lower alkyl phosphite to yield the desired di-lower alkyl 3-indolemethanephosphonate. I usually employ a considerable excess of the tri-lower alkyl phosphite to serve as a re-

2

action medium which facilitates stirring of the mixture. This reaction is preferably carried out at a temperature in the approximate range 80 degrees centigrade to 160 degrees centigrade, and at least several hours reaction time is required for optimum yields.

The di-lower alkyl 3-indolemethanephosphonates obtained as intermediates in my process are white solids which are practically insoluble in water and are moderately soluble in ethanol. They are hydrolyzed by aqueous alkaline solutions to the corresponding mono-lower alkyl esters which, like the di-lower alkyl esters, are hydrolyzed by strong mineral acid—glacial acetic acid mixtures to yield 3-indolemethanephosphonic acid.

In the second, or acid hydrolysis, step of my process, the di-lower alkyl 3-indolemethanephosphonate resulting from the first step is heated, conveniently at reflux temperature, for several hours or more with a mixture of glacial acetic acid and a strong mineral acid, such as hydrochloric acid, phosphoric acid, or sulfuric acid. This procedure removes both of the lower alkyl groups and produces the free dibasic acid, 3-indolemethanephosphonic acid. This white crystalline product is readily isolated and easily purified. It can be used as such or converted to any desired salt by conventional treatment with the appropriate organic or inorganic base.

My invention is illustrated by the following examples without, however, being limited thereto.

EXAMPLE 1

A. Diethyl 3-indolemethanephosphonate

7.1 g. of methyl iodide was dripped into a stirred suspension of 8.7 g. of gramine in 65 g. of triethyl phosphite at room temperature (about 25 degrees centigrade) during a period of fifteen minutes, and the reaction mixture was then heated for ten hours on a steam bath. After this heating period, the reaction mixture was filtered to remove the solid material which had separated from solution, and the collected solid was washed with about 25 ml. of benzene. The filtrate and wash liquor were combined and concentrated under reduced pressure, and the residue thus obtained, which weighed 25 g., was shaken with a mixture of ether and water. The ether layer was separated and concentrated, and then distilled. After a small fore-run of triethyl phosphite had distilled, the boiling point of the residual liquid rose rapidly. The fraction of product distilling at 196-196.5° C. (uncorr.) at 0.3 mm. pressure was collected as a viscous yellow oil. This oil, which weighed 9.5 g., crystallized on standing, and the solid product was recrystallized from ethanol-hexane to yield white crystals melting at 57-60° C. The product thus obtained was diethyl 3-indolemethanephosphonate, having the structural formula

Analysis.—Calculated for $\text{C}_{13}\text{H}_{18}\text{NO}_3\text{P}$: Nitrogen, 5.24%; oxygen, 17.96%. Found: Nitrogen, 5.21%; oxygen, 17.90%.

When equivalent amounts of 3-diethylaminomethyl-indole and 3-(piperidinomethyl)indole are substituted for the gramine reactant in the above procedure, there is obtained in each instance the same product as above described, namely diethyl 3-indolemethanephosphonate.

B. 3-indolemethanephosphonic acid

5.1 g. of diethyl 3-indolemethanephosphonate was dissolved in a mixture of 25 ml. of acetic acid and 25 ml.

of concentrated hydrochloric acid, and the resulting solution was refluxed for nine hours. The reaction was then concentrated under reduced pressure. The crystalline residue thus obtained was recrystallized from 30 ml. of water and then from 13 ml. of water, thereby yielding 2.1 g. of almost-white crystals which melted at 216.8-218.4° C. (corr.). This product was 3-indolemethanephosphonic acid, having the structural formula

Analysis.—Calculated for $C_{13}H_{18}NO_3P$: Nitrogen, 6.63%; neutral equivalent, 106. Found: Nitrogen, 6.54%; neutral equivalent, 110.

This acid is soluble in water at 25° C. to the extent of about 0.5% (weight/volume). The pH of a 0.5% solution was 2.2; when a 0.5% aqueous solution was adjusted to pH 7.0 by treatment with N/10 sodium hydroxide solution, no precipitate was formed. The acid was soluble in diethyl ether and fairly soluble in isopropyl alcohol.

3-indolemethanephosphonic acid reacted with inorganic and organic bases to form the corresponding mono- or di-salts, depending on whether one or two equivalents of base was employed. The water-soluble alkali metal salts and the ammonium salts are especially useful and economical forms for many purposes, but other salts are also readily obtained and may be preferred in some instances, for example: the alkaline earth metal salts, for instance the calcium, magnesium, and barium salts; the copper, mercury, and arsenic salts; and substituted-ammonium salts, for instance the dimethylammonium and triethanolammonium salts.

The mono and disodium salts are preferred salts of the new dibasic acid of this invention. These are obtained in conventional fashion, as by interacting one or two equivalents of sodium hydroxide with the acid. These salts are readily water-soluble.

EXAMPLE 2

A. Monoethyl 3-indolemethanephosphonate

Alkaline hydrolysis of diethyl 3-indolemethanephosphonate, for instance by heating it for several hours with 5% sodium hydroxide solution, produces ethyl sodium 3-indolemethanephosphonate, which on treatment with one equivalent of hydrochloric acid or other strong acid is converted to monoethyl 3-indolemethanephosphonate, M.P. 136-137° C., having the structural formula

B. 3-indolemethanephosphonic acid

Acid hydrolysis of the monoethyl 3-indolemethanephosphonate described in part A above, using the same hydrolysis conditions as described in part B of Example 1, produces 3-indolemethanephosphonic acid, identical with the product from the acid hydrolysis of the diethyl ester.

EXAMPLE 3

A. Di-n-butyl 3-indolemethanephosphonate

By substituting 98 g. of tri-n-butyl phosphite for the triethyl phosphite and 6.3 g. of dimethyl sulfate for the methyl iodide in the procedure described in part A of

Example 1, there is obtained di-n-butyl 3-indolemethanephosphonate, having the structural formula

B. Mono-n-butyl 3-indolemethanephosphonate

By hydrolysis of di-n-butyl 3-indolemethanephosphonate with aqueous potassium hydroxide solution to produce n-butyl potassium 3-indolemethanephosphonate and treating this ester-salt with strong acid, there is obtained the mono ester having the structural formula

C. 3-indolemethanephosphonic acid

Hydrolysis of di-n-butyl 3-indolemethanephosphonate and mono-n-butyl 3-indolemethanephosphonate with a mixture of concentrated hydrochloric acid and glacial acetic acid produces, in each instance, 3-indolemethanephosphonic acid.

3-indolemethanephosphonic acid and its salt inhibit the plant growth stimulating properties of heteroauxin. This inhibition can be readily determined by means of standard biological test procedures. For instance, the following method is used. An aqueous solution containing

$10^{-5}\gamma$ of heteroauxin per ml. is employed as a control. A series of aqueous test solutions containing 3-indolemethanephosphonic acid, or mono or disodium salt thereof, at concentrations of 1 up to 1000 per ml., is prepared and to each solution there is added sufficient heteroauxin

so that its concentration in the solution is $10^{-5}\gamma$ per ml. These solutions are then applied to the roots of a test plant, such as *Lepidium sativum*, and the plants are incubated at 27° C. in the dark for 12-18 hrs. By measuring the root lengths before and after the test and comparing the controls with the test solutions, the antagonistic effect of the various concentrations of 3-indolemethanephosphonic acid, or salt thereof, can be calculated in terms of the percentage difference in root lengths.

The normal stimulation of root growth by the heteroauxin is diminished by the presence of the 3-indolemethanephosphonic compound, so that the root lengths are shorter in the test solutions than in the controls.

My new compounds can be employed to combat the growth of unwanted vegetation by application to the plants by the conventional methods, for instance dusting, spraying, and the like. When spraying is used, I generally prefer an aqueous solution of the monosodium or disodium salt of 3-indolemethanephosphonic acid.

3-indolemethanephosphonic acid has a relatively low toxicity toward animals; for example, oral doses in the range 100-200 mg./kg. had no detectable effect on cats or monkeys.

I claim:

1. 3-indolemethanephosphonic acid, having the struc-

ture formula

2. An alkali metal salt of 3-indolemethanephosphonic acid.

3. A sodium salt of 3-indolemethanephosphonic acid.

2. An alkali metal salt of 3-indolemethanephosphonic acid.

3. A sodium salt of 3-indolemethanephosphonic acid.

5

4. The process which comprises: heating a mixture of a tri-lower alkyl phosphite and a 3-indolemethyl-²⁰ quaternary ammonium salt having the structural formula

5

where B represents a member of the group consisting of dimethyl, diethyl, and 1,5-pentylene radicals, and An represents a member of the group consisting of the iodide radical and the metho-sulfate radical; and hydrolyzing the resulting di-lower alkyl 3-indolemethanephosphonate by heating it with a mixture of a strong mineral acid and glacial acetic acid to produce 3-indolemethanephosphonic acid.

5. The process which comprises: heating a mixture of triethyl phosphite and N-(3-indolemethyl)-N,N,N-tri-methyl-ammonium iodide; and hydrolyzing the resulting diethyl 3-indolemethanephosphonate by heating it with a mixture of glacial acetic acid and hydrochloric acid to produce 3-indolemethanephosphonic acid.

6. The process which comprises heating a mixture of

25 a tri-lower alkyl phosphite and a 3-indolemethyl quaternary ammonium salt having the structural formula

6

10 where B represents a member of the group consisting of dimethyl, diethyl, and 1,5-pentylene radicals and An represents a member of the group consisting of the iodide radical and the methosulfate radical, to produce a di-lower alkyl 3-indolemethanephosphonate.

15 7. A compound of the group consisting of mono-lower alkyl 3-indolemethanephosphonates and di-lower alkyl 3-indolemethanephosphonates.

8. Diethyl 3-indolemethanephosphonate.

UNITED STATES PATENT OFFICE
CERTIFICATION OF CORRECTION

Patent No. 2,980,692

April 18, 1961

Noel F. Albertson

It is hereby certified that error appears in the above numbered patent requiring correction and that the said Letters Patent should read as corrected below.

Column 1, lines 30 to 33, column 5, lines 4 to 7, and column 6, lines 3 to 6, the right-hand portion of the formulas, each occurrence, should appear as shown below instead of as in the patent:

column 2, line 64, for "3-diethylaminomethyl)-" read -- 3-(diethylaminomethyl)- --; column 4, line 30, for "salt" read -- salts --.

Signed and sealed this 26th day of September 1961.
